UNITED STATES PATENT OFFICE

170,403

BRACELET OR SIMILAR ARTICLE

Georges de Saint-Germain, Long Beach, Calif.

Application January 2, 1952, Serial No. 17,904

Term of patent 3½ years

(Cl. D45—4)

To all whom it may concern:

Be it known that I, Georges de Saint-Germain, a citizen of France, residing at Long Beach, State of California, have invented a new, original, and ornamental Design for a Bracelet or Similar Article, of which the following is a specification, reference being had to the accompanying drawing, forming a part hereof.

I claim:

The ornamental design for a bracelet or similar article, substantially as shown.

GEORGES DE SAINT-GERMAIN.
